UNITED STATES PATENT OFFICE.

ALFRED P. KRAUSE, OF SEATTLE, WASHINGTON.

CAN-OPENER.

1,183,741.

Specification of Letters Patent. Patented May 16, 1916.

Application filed July 16, 1915. Serial No. 40,296.

To all whom it may concern:

Be it known that I, ALFRED P. KRAUSE, a citizen of the United States, residing at Seattle, in the county of King and State of Washington, have invented certain new and useful Improvements in Can-Openers; and I do hereby declare the following to be a full, clear, and exact description of the invention, such as will enable others skilled in the art to which it appertains to make and use the same.

This invention relates to can openers, and one of the principal objects of the invention is to provide a can opener of simple construction which can be readily adjusted for cutting the tops out of cans of various sizes.

Other objects will appear from that embodiment of my invention of which the following is a specification, reference being had 20 to the accompanying drawings forming a part thereof, in which:

Figure 1 is a side elevation of the can opener. Fig. 2 is a top plan view thereof, and Fig. 3 is a longitudinal section taken 25 through Fig. 1.

Referring to the drawings more in detail, the numeral 1 designates the shank of a can opener comprising a flat metal bar having a longitudinal slot 2 therein. One end of the 30 shank is provided with a centering prong 3 which is adapted to be driven into the center of the top of the can and during the opening of the can.

Associated with the shank 1 and underlying the said shank are a pair of cutter bars 35 designated 4 and 5 respectively. The lowermost cutter bar 5 has one end extending downwardly to provide a cutter 6. The uppermost cutter bar 4 has one end extended 40 downwardly in parallel relation with the cutter 6 and the cutter bar 4, as shown at 7, and then extended laterally to provide a horizontally disposed cutter 8.

Located above the shank 1 is a sliding 45 plate 9. This sliding plate has one end extended upwardly, as shown at 10, to provide a finger hold, and the said plate is adapted to be secured to the cutter bars 4 and 5 by means of fastening bolts 11 and 12, which 50 extend through the sliding plate 9 and through the elongated slot 2 and have their lower ends threadedly received in alined

openings in the superposed cutter bars 4 and 5. The shank 1 has its end opposite the one carrying the centering prongs 3, formed to 55 provide a handle 13. Located beneath the handle 13 is a bowed leaf spring 14, one end 15 of which is secured to the free end of the handle 13 by means of the fastening screw 16, the opposite end of the spring 14 being 60 extended and underlying the lowermost cutter bar 5 and is secured thereto by means of the fastening bolt 12, as shown in Fig. 1 of the drawing.

In operation the centering prong 3 is first 65 driven through the can top and the shank 1 lowered to horizontal position. The finger hold is then grasped and rearward pull is exerted thereon so as to cause the sliding plate 9 and the cutter bars 4 and 5 to be 70 pulled in the direction of the handle 13, and until the cutter 6 is positioned at a point adjacent the marginal edge of the top. The cutter 6 is then forced through the top and the shank given a circular motion around 75 the can, resulting in the severing of the top. When it is desired to open the can at a point below the can top the centering prong 3 is driven through the can top, in the manner before described, and the sliding plate and 80 the cutter bars 4 and 5 pulled rearwardly in the direction of the rear end of the slot 2. The shank is then lowered to the horizontal and the cutter 5 positioned against the side 85 of the can at a point adjacent the top and driven through the same. The shank is then given a circular motion around the can resulting in the can being opened at a point on the side and adjacent the top. The spring 14 is to keep the cutter 5 in cutting position, 90 when the said cutter 5 is applied; also to return the sliding plate and the cutter 5 to their normal position after the opening of the can.

Various changes may be made in the details of construction without departing from the spirit and scope of the invention as defined in the claim.

What is claimed is:

A can opener comprising a shank having 100 a handle on one end thereof, cutters disposed beneath the shank and slidably thereon, means for holding the cutters to the shank, a bowed spring disposed beneath the

handle and having one end secured to the rear end of the handle and its opposite end secured to the holding means for the cutters, the said spring serving to force the cutters toward the forward end of the shank, and when flexed to draw the cutters toward the handle, as and for the purpose specified.

In testimony whereof I affix my signature in presence of two witnesses.

ALFRED P. KRAUSE.
